UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER WITH CONCAVE TEETH.

1,329,328.

Specification of Letters Patent.

Patented Jan. 27, 1920.

Application filed July 18, 1918. Serial No. 245,563.

To all whom it may concern:

Be it known that I, EDWARD S. STIMPSON, of Hopedale, in the county of Worcester and State of Massachusetts, have invented a new 5 Feeler with Concave Teeth, of which the following is a specification.

The new feeler mechanism includes a sliding and swinging feeler which slides forward and back during the normal running 10 of the loom and which tends to move lengthwise of the bobbin being restrained from such movement by the weft on the bobbin. When, however, the weft approaches exhaustion the feeler tip encounters the smooth 15 surface of the bobbin and slips along the bobbin, the feeler as a whole then swinging laterally. This lateral movement is utilized to set into action a train of weft replenishing mechanism with the result that the 20 nearly depleted bobbin (or the shuttle carrying it) is ejected and a filled bobbin (or a shuttle carrying a filled bobbin) is brought into action. Except in the respects to be 25 particularized the feeler mechanism herein set forth is similar to that illustrated and described in Letters Patent of the United States, Number 1,309,226, dated July 8, 1919. The present improvement relates to the 30 feeler tip and its relation to the laterally slipping feeler arm and to the bobbin and the weft carried thereby.

The improvement is illustrated in the accompanying drawings in which—

Figure 1, is a plan view of so much of the 35 detecting side of the loom as is necessary for an understanding of the improvement. In this figure the front walls of the shuttle and of the shuttle box are shown in section, and the parts are shown in the position which 40 they occupy just as the weft first encounters the feeler tip during the forward swing of the lay. Fig. 2, shows on an enlarged scale the initial contact between the weft and feeler tip. Fig. 3, is a detailed vertical section in the plane indicated by the line 3—3 45 in Fig. 2. Fig. 4, illustrates approximately the condition which occurs following the encounter of weft and feeler tip, indicating to an exaggerated extent a penetration of the 50 teeth into the weft. Fig. 5, illustrates the conditions following the encounter between the feeler tip and the bare bobbin.

The feeler comprises a feeler arm A, and a feeler tip B. The feeler arm is mounted

so as to both slide and swing and it is shown 55 as inclined to the forward and aft swing of the lay and with the feeler tip offset laterally inward as compared with the forward end and pivot of the feeler arm, in this respect being similar to the feeler arm set forth in 60 said patent. As a consequence of this disposition of the feeler arm the impact of the forwardly moving bobbin C, tends to swing the feeler tip laterally inward, that is to say 65 toward the middle of the loom and the tip 70 of the bobbin and away from the butt of the bobbin. As long, however, as weft D, is present on the bobbin opposite the feeler tip the engagement of the weft with the feeler tip teeth E, prevents such lengthwise slipping. Fig. 4, illustrates to an exaggerated degree, for the sake of clearness, how there 75 is a sufficient penetration of the teeth E, into the weft D, to prevent the slipping of the tip lengthwise of the bobbin C.

When, however, the feeler tip teeth encounter the smooth surface of the bare bobbin, as indicated by dotted lines in Fig. 5, the impact of the bobbin on the inclined 80 feeler causes the feeler to swing and the teeth E, to slip along the bobbin to a position as indicated by full lines in Fig. 5. This lateral swing is utilized to set the weft 85 replenishing train into action.

As thus far referred to the organization 85 and mode of operation are similar to those of the aforesaid patent. In accordance with the present improvement, the feeler tip B, is rigidly and immovably secured within the socketed free rear end of the feeler arm A. 90 The feeler tip has a plurality of teeth E, four being shown. The teeth are blunt and rounded so that there is no danger of either cutting the weft or scratching the bobbin. Each tooth is vertically concave on its rear 95 weft-contacting face, the curvature being such as to conform substantially to the convex surface of the weft, as shown in Fig. 3. Transversely, a line along the ends of the teeth, as shown in Fig. 2, is parallel with 100 the normal axis of the bobbin. This disposition of the teeth is such that there is adequate engagement of the weft to prevent premature slipping of the feeler tip lengthwise of the bobbin, and a few small teeth 105 suffice. When, however, the bobbin is bare opposite the feeler tip the teeth slip along and tilt on the bobbin as indicated in Fig.

5, so that only one tooth touches the bobbin after the tilt begins. The rounded teeth slip readily along the bare bobbin.

The accompanying drawings illustrate only 5 enough of the feeler supporting and co-operating mechanism to enable the sliding and swinging movements of the feeler arm to be understood since in these respects the mechanism is identical with that shown in the aforesaid patent. The feeler arm A, is mounted 10 on a bracket I, attached to a lateral extension J, of the breast beam. A rock shaft K, is journaled to the forward end of the bracket turning on a vertical axis. This rock 15 shaft has a through-aperture through which the front end of the feeler arm extends and slides. At its rear end the feeler arm extends through a broad passageway in the bracket, the margins of this passage-way being indicated by the dotted lines L, L. The 20 top of this passageway is closed by a cap M, which with the bottom of the bracket confines the feeler arm against vertical movement. Secured to the feeler arm near 25 its middle is a slide N, which slides on horizontal ways O, of the bracket. A spring Q, surrounds the feeler arm between the slide N, and the rock shaft K, and normally holds the feeler arm in its rearward position with 30 the slide against the shoulders of the bracket which support the cap M. The feeler arm is also maintained by the spring against the outer wall L, of the passage-way. In this 35 normal position the feeler arm extends at an angle to the fore and aft swing of the lay. Consequently, the rock shaft K, is offset laterally and outwardly with respect to the passageway so that the feeler arm stands at an angle to the fore and aft swing of 40 the lay and the bobbin (or the weft thereon) encounters the tip along a fore and aft path nearer the tip of the bobbin than a parallel path intersecting the rock shaft. So long as the weft on the bobbin encounters 45 the teeth of the tip the resistance thus offered prevents any slipping of the tip lengthwise of the bobbin. Accordingly as the lay moves forward after the first encounter of the weft with the tip there is no 50 sliding of the tip on the weft; but during the completion of the forward movement of

the bobbin the feeler arm is moved forwardly compressing the spring Q. During this normal action there is a slight inward swing (to the right) of the feeler arm permitted by the turning of the rock-shaft. When the bobbin is bare opposite the feeler tip there is a further inward lateral swing of the feeler arm to the right and this additional swing is utilized to set in action the 60 train of weft replenishing mechanism.

This functional swing of the feeler arm under the impact of the bare bobbin causes the feeler arm to encounter a controller X, and move it laterally inward. This controller is mounted in a transverse guide-way of the bracket J, as shown in dotted lines and it has a slot Z, through which the feeler arm passes. This slot is sufficiently wider than the width of the feeler arm so that the 65 normal swing of the feeler arm has no effect on the controller. When, however, the functional swing of the feeler arm is imparted to it by the lengthwise movement of the feeler tip along the bobbin the controller is 70 slid laterally inward. This lateral movement of the controller is utilized to bring about weft replenishment as explained in detail in the aforesaid patent. After the 75 functional action has occurred a fixed cam 80 W, on the bracket acts upon a projection on the feeler arm to restore the feeler arm to its normal position as it retreats under the influence of the spring Q.

The weft D, is so wound on the bobbin 85 that there is a sufficient amount to continue the weaving after the feeler tip has performed its functional slip and until weft replenishment has been effected.

I claim—

1. A laterally slipping feeler arm with a 90 fixed tip having a plurality of blunt rounded teeth each with a concave face conforming to the curvature of the weft on the bobbin.

2. A laterally slipping feeler arm having a plurality of blunt rounded teeth each with a concave face.

In witness whereof, I have hereunto signed my name.

EDWARD S. STIMPSON.
